CORNER JOINT FOR WALLBOARDS

Cecil K. Barger, Statesville, N. C.

Application October 10, 1944, Serial No. 557,979

2 Claims. (Cl. 20—92)

1

This invention relates to a corner joint for the vertical corners of a room, or for the corners formed by the ceiling or floor and vertical side walls of a room.

It is an object of this invention to provide a joint for the converging side walls of a room or a joint for the junction point between the ceiling or floor and the side walls of a room, which will prevent opening up and forming of a crack at the junction point between the side walls in the corner of the room or the junction point between the ceiling or floor and one of the side walls, and thus preventing the necessity of having to use a molding at the junction point to cover the seam formed between the two converging sheeting members forming the interior surface of a room.

It is another object in this invention to provide a corner structure for a room in a building which will cause the ceiling or wall portions of the room to remain in fixed position and prevent seams or cracks forming between the junction points of the sheet members forming the walls of the room.

Some of the objects of the invention having been stated, other objects will appear as the description proceeds when taken in connection with the accompanying drawings, in which

Figure 1 is an exploded isometric view of the parts making up the joint.

Figure 2 is a horizontal sectional view taken through the two wall portions forming a projecting corner in a room.

Figure 3 is a vertical sectional view taken through the upper portion of a room and through the ceiling covering and the wall covering or it can be a horizontal sectional view taken through the corner of a room and cutting through the two wall portions forming the inside covering of the walls of the room.

Figure 4 is a sectional view taken along the line 4—4 in Figure 3.

Referring more specifically to the drawings, the numeral 10 indicates a corner upright or a horizontal member disposed above the ceiling of the room, while numeral 11 indicates another timber which may be a corner post or a horizontal member disposed at the top of the wall of a room. If these numbers 10 and 11 represent corner posts, then the plywood member is adapted to be placed in vertical position and secured to these two timbers 10 and 11. The plywood member is composed of a plurality of sheets of veneer 12 and 13 and shaped wood members 15 and 16. The members 12, 13, 15 and 16 are securely glued

together in a suitable press to form a right angle member of any suitable length, which extends from one wall of the room to the other when used as a joint between the ceiling and one of the walls, and also extends from the floor to the ceiling if used as a vertical corner joint member.

This plywood member composed of veneers 12 and 13 and shaped wood strips 15 and 16, is fastened to framing members 10 and 11 by nails 17, or by any other suitable fastening agent, except glue or other permanent adhesive.

After this plywood member is placed in position, whether it be in vertical or horizontal position, the sheeting members 18 and 19, which form the wall or ceiling covering, are placed in position. Before placing the sheeting members 18 and 19 in position, however, the exposed contact surfaces of the plywood member are covered with a suitable adhesive 20, such as glue, and then the sheeting members 18 and 19 are placed in position, and are suitably secured along the walls, either by gluing or by nailing or otherwise, and thus a secure joint is provided, which, due to the gluing of the wallboards 18 and 19 to the common plywood member, will provide a homogeneous structure, which will cause the members 18 and 19 to become an integral part of the plywood member and, therefore, if the timbers 10 and 11 should tend to separate, the plywood member will have a tendency to prevent the separation of members 18 and 19.

It is thus seen that there has been provided a building joint adapted to be used in the placing of the sheeting covering over the interior surfaces of the walls of any room and placing the ceiling or floor in position, and which provides a corner structure which holds the sheeting members in proper position and prevents separation at their junction point to provide an opening up and causing ugly cracks which heretofore it has been necessary to obscure by placing a molding member such as a quarter-round thereover.

Although the angle member to be composed of two strips of veneer and two shaped wood strips, and of a right angular nature have been shown and described, it is to be understood that if made of wood, the angular member may have more layers than shown, or it may be of an angularity other than that of a right angle to suit conditions, or it may be made of metal, plastic, textile or other suitable material.

In the drawings and specifications, there has been set forth a preferred embodiment of the in-

vention, and although specific terms are employed, the scope of the invention is defined in the claims.

I claim:

1. Corner construction for interior wall coverings of a room in a building comprising an angular member secured to the framing members of the building and in the corner of a room, strips of material secured to the legs of the angular member and wall boards secured to the exposed surfaces of the strips, the adjoining edges of the wall board members being overlapped.

2. A corner joint for wall board linings for a room in a building having framing members adjacent the corner of the room comprising a strip of plywood bent to angular shape and adapted to extend from the floor to the ceiling of the room, vertically disposed slats disposed against the concave side of the strip of plywood, means penetrating the strip, the slats and the framing

members to join them together, said strip of plywood and the slats being covered by pieces of wall board adhesively secured thereto.

CECIL K. BARGER.
